UNITED STATES PATENT OFFICE.

VIRGIL WEBB BAUMGARTNER, OF SALT LAKE CITY, UTAH.

AUTOMATIC BLOCK-SIGNAL APPARATUS.

1,228,168.

Specification of Letters Patent. Patented May 29, 1917.

Application filed February 10, 1915. Serial No. 7,429.

To all whom it may concern:

Be it known that I, VIRGIL W. BAUMGARTNER, a citizen of the United States, and a resident of Salt Lake City, in the county 5 of Salt Lake and State of Utah, have invented a new and Improved Automatic Block-Signal Apparatus, of which the following is a full, clear, and exact description.

This invention relates to automatic block signal systems especially adapted, although not necessarily limited, to single track traffic, the system contemplating the use of green, yellow and red signal lamps at the ends of each block, whereby the traffic conditions can be reliably governed by pre-arranged signals; that is to say, normally the green signal lamps will be lighted when the block is clear, and when a train enters a block a red signal will be exhibited at 10 the far end and a yellow signal at the entering end, and when the train or car leaves the block the green lamps will be restored and the other lamps cut out of service, and when two trains or cars enter opposite ends 15 of the block at the same time there will be exhibited at each end a yellow and a red lamp, so that the engineers or motormen will be duly warned in time to prevent a collision.

30 The invention has for its general objects to provide a reliable and effective signal system which is of comparatively simple and inexpensive construction and entirely automatic in operation.

35 Another object of the invention is the provision of a group of oil switches at each end of the block and electro-magnetically controlled by means of current derived from the trolley wire or third rail by the trolley

40 wheel or shoe engaging contacts at the ends of the block, and through the medium of the oil switches, the signal lamps will be connected with the trolley wire or third rail according to a pre-arranged plan of signaling.

45 A further object of the invention is the provision of a novel arrangement of electro-magnets associated with each oil switch for opening and closing the contacts of the latter, the electro-magnets having interlocking armatures whereby the oil switch will remain open or closed until the opening or closing electro-magnet is energized.

50 Still another object of the invention is to provide a novel arrangement of contacts associated with the trolley wire, whereby the

flanges of the trolley wheel will engage the contacts and thereby supply current from the trolley wheel to the contacts and from the latter to the signal system.

With such objects in view, and others which will appear as the description proceeds, the invention comprises various novel features of construction and arrangement of parts which will be set forth with particularity in the following description and claims appended hereto.

In the accompanying drawings, which illustrate one embodiment of the invention and wherein similar characters of reference 70 indicate corresponding parts in all the views,

Figure 1 is a side view of a pair of contact devices at each end of a block, portions being broken away;

Fig. 2 is a vertical section on the line 75 2-2, Fig. 1;

Fig. 3 is a side view of one of the oil switches;

Figs. 4 and 5 are diagrammatic views of the signal system showing respectively the 80 condition after a car has entered a block and the condition when it is about to leave the far end of the same; and

Fig. 6 is a diagrammatic view showing the condition of the system when the car has 85 entered the left end of the block.

In the present instance the contact devices at the ends of the block are designed for use in connection with a trolley wire 10. Each contact device A comprises a horizontal bar 90

11 of insulation. This bar of insulation, which is disposed above the trolley wire 10, has on its ends hangers 12 which are rigidly secured to the trolley wire, and cross-rods or other supports 13 hold the bar 11. Under 95

the bar and disposed slightly above the trolley wire 10 are contacts 14 and 15 in the form of horizontal metallic strips which are each fastened to a pair of oppositely disposed V-shaped springs 16 that are in turn 100 fastened to the under side of the bar 11. The

springs allow the contacts 14 and 15 to yield upwardly when the flanges 17 on the trolley wheel 18, Fig. 1, pass under the contact device A. The springs 16 are riveted to a strip 19, and this in turn is fastened by bolts 20 to the bar 11, and these bolts form binding posts for connecting certain wires of the system with the contacts 14 and 15.

Also at each end of a signal block is arranged a group of lamps L for indicating the conditions of traffic in the blocks, each

group of lamps being suitably arranged, as in a box 21, and each group including a green lamp *g*, a yellow lamp *y*, and a red lamp *r* arranged in independent circuits.

5 The circuits of the signal lamps are controlled by oil switches, one for each signal lamp. Each switch comprises a fixed contact 22 and a movable contact 23, both of which extend into a cup or receptacle 24 containing an insulating oil 25 for preventing arcing when the contacts are separated. The fixed contact 22 is secured to a block of insulation 26 and the movable contact 23 is fastened to an armature 27 of an electro-magnet 28, the armature being pivoted at 29 on the metallic frame 30 of the electro-magnet. The electro-magnet 28 serves to open the oil switch, and a spring 31 connected with the armature 27 serves to close 10 the switch. The closing of the switch is controlled, however, by an electro-magnet 32 which has an armature 33 that interlocks with the armature 27 when the latter is in switch-open position, as shown in Fig. 3. 15 The armature 33 has a spring 34 which, like the spring 31, is adjustably connected with a bracket or other support 35 which is fastened to the frame 30 for the magnets 28 and 32. The armatures 27 and 33 are disposed at approximately right-angles to each other with their free ends in proximity, so that the free end of one armature will interlock with the free end of the other armature. Thus, when either magnet is energized it will attract its 20 associated armature and the armature of the other electro-magnet will be drawn by its spring into interlocking relation with the magnetically attracted armature, it being understood that the magnets are never energized simultaneously. For instance, when the opening magnet 28 is energized, the armature 27 is attracted, so that the oil switch is opened, and the armature 33 of the closed electro-magnet will drop under the 25 free end of the armature 27. The parts remain in this position until the closing magnet 32 is energized, the effect being that the armature 33 is attracted and the free end of the armature 27 will drop under the free end of the armature 33. Each armature has on 30 its under side a stop 36 for limiting the movement of one armature under the other.

In the diagrams the oil switches *G*, *Y* and *R* constitute a group at one end of a block 35 for the green, yellow and red lights, respectively, and the switches *R'*, *Y'*, and *G'* constitute the group at the other end of a block for controlling green, yellow and red lights, respectively. Three wires 37, 38 and 39 extend the length of a block, and the wire 37 is connected with the end contacts 14 of the contact devices *A* associated with the trolley wire, and the wire 38 is connected with the contact 15 of the contact device at one end 40 of the block, while the wire 39 is connected

with the contact 15 of the contact device at the opposite end of the block. The closing magnets 32 of the switches *G* and *G'* are connected by the branch wires 37^a with the wire 37, and the opening magnets 28 of the switches *Y*, *Y'* and *R*, *R'* are connected by wires 37^b with the supply wire 37. The opening magnets 28 of switches *G* and *G'* are made with two windings which are connected respectively with branches 38^a and 39^a of the supply wires 38 and 39, respectively. The closing magnets 32 of the switches *Y* and *Y'* are connected respectively by branches 38^b and 39^b with the wires 38 and 39 respectively, and the closing magnet 32 of the switches *R* and *R'* are respectively connected in series with the supply wires 39 and 38, and it will be noted that all the magnets other than the last two are connected to ground by ground wires 40. In order to reduce the quantity of current flowing through the electro-magnets, resistances 41 are arranged in series between the magnets and the supply wires 37, 38 and 39, that are adapted to be connected with the 50 trolley wire 10 as the trolley wheel engages the contacts 14 and 15.

The lamps are connected with the trolley wire by a common wire 42, and separate wires 43, 44 and 45 extend from the respective lamps *g*, *y* and *r* to the fixed contacts 22 of the switches *G*, *Y* and *R*. The metallic frames 30 for the electro-magnets are connected with the ground wire 40, so that when an oil switch is closed the circuit is completed through the frame of the magnets thereof.

When a block is clear the green lamps *g* at both ends of the block will be lighted and current flows from the trolley wire 10 through the wire 42, lamp *g*, wire 43, contacts of the normally closed switches *G* and *G'*, magnet frames 30 and wire 40, to ground. When a car enters a block the trolley wheel will make contact with the outer contact 14, but this will have no effect on the lamps except that the green lamps will continue to glow for an instant until the trolley wheel engages the adjacent contact 15, as shown in Fig. 4, where the trolley wheel 18 of the car is supposed to be moving from the right to left. When the trolley wheel 18 engages the contact 15 the normally closed green light switches *G* and *G'* are opened and the yellow light switch *Y'* and the red light switch *R* also closed, so that current will flow through the path indicated by the heavy lines in Fig. 4. This means that a red lamp will be lighted at the far or leaving end of the block and the yellow light at the entrance end. This condition will be maintained until the car leaves the block. In leaving the block the trolley will engage the contact 15 at the leaving end, but this has no operative effect.

fect in the scheme of signaling, and it is only when the trolley wheel engages the contact 14 at the leaving end of the block that an effective change in the signaling 5 takes place, as shown in Fig. 5. From this diagram it will be seen that all the oil switches except the switches G and G' are open, and consequently current will flow through the circuits indicated by the heavy 10 lines, and therefore the green lamps will be again energized to show that the block is clear. The change which has been brought about by the car leaving the block is the opening of the switch Y' in addition to the 15 closing of switches G and G' and the opening of the switch R.

In Fig. 6 it is assumed that the car is traveling to the right and that the trolley wheel is in engagement with the left 20 contact 15. As a consequence the oil switches Y and R' are closed, so that current will pass through the yellow lamp of the left group and the red lamp of the right group, whereby a caution signal will 25 be exhibited at the entrance end of a block and a danger signal at the leaving end. When the car passes out of the block the 30 circuits will be restored to normal condition, with the green lamps at both ends of the block lighted and all the oil switches open, except the switches G and G'.

From the foregoing description taken in connection with the accompanying drawings, the advantages of the construction and 35 method of operation will be readily understood by those skilled in the art to which the invention appertains, and while I have described the principle of operation, together with the apparatus which I now 40 consider to be the best embodiment thereof, I desire to have it understood that the apparatus shown is merely illustrative and that such changes may be made when desired as are within the scope of the append- 45 ed claims.

Having thus described my invention, I claim as new and desire to secure by Letters Patent:

1. The combination of track rails, with a 50 block signal system independent of the track rails and comprising a clear signal at the entering end of the block and a clear and a danger signal at the leaving end of the block, a switch for each signal 55 to complete the circuit thereof, electrical means for closing the clear signal switches as a car is leaving the block for setting clear signals, electrical means for closing the danger signal switch and opening the clear signal switches as a car enters 60 the block, whereby a danger signal is given at the far end of the block, each switch including an electro-magnetically operated movable contact for opening the switch, and 65 an electrically operated lock movable to and

from a position for holding the movable contact in open position.

2. The combination of track rails, with a block signal system independent of the track rails, and comprising an energized conductor 70 extending along the block, clear and danger signals at each end of the block, and connected with the conductor, a pair of yieldingly mounted contacts associated with the conductor at each end of the block, a car- 75 carried element engaging the conductor and adapted to strike the said contacts to electrically connect the same with the conductor, normally closed switches for completing the circuits of clear signals, electrical means 80 connected to one of the said contacts at each end of the block for opening the said switches as the said element enters either end of a block to destroy the clear signals, electrical means connected to the other of said 85 contacts at each end of the block for effecting the closing of the said switches when the car-carried element leaves the remote end of the block, a normally open switch adapted when closed to complete the circuit of the 90 danger signal at the remote end of the block, electrical means connected with the first mentioned contact at the entering end of the block, for closing the last mentioned switch when the car carried element enters the 95 block, and means connected with the second mentioned contacts for opening the danger signal switches simultaneously with the closing of the clear signal switches, as the car- 100 carried element leaves the remote end of the block, each of said switches comprising a movable contact, an electromagnet adapted when energized to operate the contact to open the switch, locking means for holding the said contact in open position, an electromagnet controlling said locking means and adapted when energized to release the movable contact, and means for moving the said contact to closed position when released.

3. The combination of track rails, with a block signal system independent of the track rails and comprising an energized conductor, an element carried by a car and engaging the conductor, a pair of contacts at each end of the block and associated with the conductor, whereby the said element in passing the contacts electrically connects the contacts with the conductor, clear and danger signals at each end of the block and connected with the conductor, normally closed clear signal 115 switches for completing the circuits of the clear signals, electrical means connected with one of said contacts at each end of the block, for opening the said switches, when a car enters either end of the block, electrical means connected with the other contacts at each end of the block for effecting the closing of the clear signal switches when a car is leaving the remote end of the block, normally open danger signal switches for clos- 120 125 130

ing the circuit of each of the danger signals, electrical means connected with the first mentioned contacts for effecting the closing of the danger signal switch at the remote 5 end of the block as a train enters the block, and electrical means for opening the closed danger signal switch, as the train is leaving the remote end of the block, each of said switches including a fixed and a movable 10 contact, an electromagnet adapted when energized to control the movable contact to open the switch, locking means for holding the movable contact in open position, an electromagnet adapted when energized to move the locking means to release the said contact, and resilient means for moving the said contact to closed position when released.

4. The combination of track rails on which cars travel in both directions, with a 20 block signal system comprising clear, danger and caution signals at each end of the block, a pair of contacts at each end of the block, an element carried by a car and adapted to engage the said contacts and connect the 25 same with a source of current, said contacts being spaced apart in the direction of travel of the car, whereby the element engages the contacts successively when the car passes through the block from either end, normally 30 closed clear signal switches for energizing the clear signals, electrical means for opening the said switches when the element engages the inner one of the contacts at the entering end of the block when the car is 35 passing through the block in either direction, electrical means for effecting the closing of the switches when the element engages the outer one of the contacts at the remote end of the block, normally open danger 40 signal switches, electrical means for effecting the closing of the danger signal switch for the danger signal at the remote end of the block by the engagement of the element with the inner contact at the entering end 45 of the block simultaneously with the opening of the clear signal switches, means for opening the said closed danger signal switch by the said element engaging the outer contact at the remote end of the block simultaneously 50 with the closing of the clear signal switches, normally open caution signal switches, electrical means for effecting the closing of the caution signal switch for the caution signal at the entering end of the 55 block when said car-carried element effects the opening of the clear signal switches and the closing of the danger signal switch at the remote end of the block, and electrical means for effecting the opening of the said 60 closed caution signal switch by the said element when the latter in leaving the remote end of the block effects the closing of the clear signal switches and the opening of the closed danger signal switch, each switch including 65 an electro-magnetically operated

movable contact for opening the switch, an electrically operated lock movable to and from a position for holding the movable contact in open position, and means for closing the movable contact when released from 70 said lock.

5. The combination of track rails, with a block signal system independent of the said rails and comprising clear, danger and caution signals at each end of the block, 75 switches for controlling the circuits of the signals, there being one switch for each signal, electrical means connected with the clear signal switches and controlled by a car passing from the remote end of the block 80 to operate the said switches to set the clear signals, electrical means controlled by a car entering the block at either end to open the clear signal switches and to close the caution signal switch to set the caution signal at 85 the entering end, and to operate the danger signal switch corresponding to the danger signal at the remote end of the block to set the latter signal, each of said switches including a pair of armatures disposed at an 90 angle to each other and arranged to interlock, electro-magnets for actuating the armatures each in one direction, resilient means for moving the armatures in the opposite direction, switch contacts one of which is 95 fastened to the armature of one of the electromagnets, the said electromagnet when energized serving to move the said contact to open the switch, the armature of the other electromagnet when the latter is energized 100 releasing the armature of the first or opening magnet to permit its resilient means to move the armature to close the said switch.

6. The combination of track rails, with a block signal system independent of the said rails, and comprising clear, danger, and caution signals at each end of the block, switches for controlling the circuits of the signals, there being one switch for each signal, electrical means connected with the clear signal switches and controlled by a car passing from the remote end of the block to operate the said switches to set the clear signals, electrical means controlled by a car entering the block at either end to open the clear signal switches and to close the caution signal switch to set the caution signal at the entering end and to operate the danger signal switch corresponding to the danger signal at the remote end of the block to set the latter signal, each of said switches comprising a fixed and a movable contact, an armature carrying the movable contact, an opening electromagnet adapted when energized to attract the said armature to open the switch, an electro-magnet for controlling the closing of the switch, one of the said electromagnets being energized when the other is deenergized, the armatures of the said electromagnets being disposed at 110 115 120 125 130

- an angle to each other and arranged to interlock, resilient means connected with the said armatures for moving the same in one direction, each electromagnet when energized releasing the armature of the other electro-magnet to permit its resilient means to move it to position to lock the armature of the energized magnet, the resilient means connected with the armature of the opening magnet also serving to move the said armature, when the latter is released, into position to close the said switch, and an oil containing receptacle in which the switch contacts are submerged.
- 5 7. The combination of track rails, with a block signal system including a conductor extending the full length of the block, and independent of the rails, clear, danger and caution signals at each end of the block
- 10 electrically actuated switches controlling the signals, one switch for each signal, each switch comprising an electromagnetically operated movable contact for opening the switch, and an electromagnetically operated
- 15 lock movable to a position to hold the movable contact in open position and also movable to a position to release the said movable contact to permit the switch to close, and contact devices for controlling the actuation of the switches, each device comprising a pair of contacts spaced along the conductor at each end of the block and in close proximity to the conductor, whereby a car-carried element having a running contact with the conductor would engage the contacts when entering the block at either end, and electrically connect them with the conductor for supplying current to the switches, one contact of a pair at the entering end of the block controlling certain of said switches to destroy the clear signals, to set a caution signal at said entering end and to set a danger signal at the remote end, the other contact of a pair at the remote
- 20 end controlling certain of the switches to restore the clear signals, at both ends of the block and to put the said caution and danger signals out of service.
- 25 8. The combination of track rails, with a block signal system comprising a conductor independent of the track rails, clear and danger signals at each end of the block and connected with the conductor, switches, one for each signal for controlling the circuits of the signals, a pair of contacts at each end of the block and controlled by a car passing through the block for electrically connecting the contacts with the conductor for operating the switches, the said switches each including a movable contact, an opening electromagnet adapted when energized to move the movable contact to open position, a lock for holding the movable contact in open position, a closing electromagnet adapted when energized to move the lock to release the said movable contact, and means for moving the said movable contact to closed position when released, one of the electromagnets being deenergized when the other is energized, one of the contacts of a pair at the entering end of a block controlling certain of said switches to energize the opening magnets of the clear signal switches and the closing magnet of the danger signal switch at the remote end, the other contact of a pair at the remote end controlling certain of the switches to energize the closing electro-magnets of the clear signal switches, at both ends of the block and to energize the opening electromagnet of the danger signal switch.
